UNITED STATES PATENT OFFICE.

JAMES ALBERT MAXSON, OF COGAR, OKLAHOMA TERRITORY.

JAR.

SPECIFICATION forming part of Letters Patent No. 727,988, dated May 12, 1903.

Application filed February 24, 1903. Serial No. 144,572. (No model.)

To all whom it may concern:

Be it known that I, JAMES ALBERT MAXSON, a citizen of the United States, and a resident of Cogar, in the county of Caddo and Territory of Oklahoma, have invented a new and Improved Jar, of which the following is a full, clear, and exact description.

The object of the invention is to provide a new and improved jar for containing fruits, preserves, meats, and other food products and arranged to insure hermetic sealing of the mouth of the jar to protect the contents thereof against air, moisture, and other influences tending to spoil the goods contained in the jar.

The invention consists of novel features and parts and combinations of the same, as will be more fully described hereinafter and then pointed out in the claims.

20 A practical embodiment of the invention is represented in the accompanying drawing, forming a part of this specification, in which the figure is a side elevation of a filled jar, parts being shown in section.

25 The jar A is provided at its mouth with an external screw-thread A', on which screws the usual cap B for closing the jar. The mouth of the jar is also provided with an internal screw-thread A², on which screws the 30 thread C', forming part of a retainer C, preferably in the form of a disk made of wood or other material and provided on its peripheral surface with the screw-thread C'. On the top of the retainer-disk is formed an off-

35 set C², adapted to be taken hold of by the operator either by hand or by the use of a suitable wrench or like tool to screw the retainer inward or outward in the mouth of the jar. The screw-thread C' of the retainer is prefer-

40 ably made of cork or other elastic packing material to form a packing to insure a complete air and water tight joint between the retainer and the inner threaded face of the jar.

45 The device is used as follows: When the cap and the retainer are removed from the jar, then the latter can be filled in the usual manner, and the retainer C is first screwed into the mouth of the jar until its under side 50 engages the top of the contents of the jar, so that the retainer extends a distance from the upper edge of the mouth of the jar, as will

be readily understood by reference to the drawing. After the retainer C is in position, then a sealing material D—such as water, 55 wax, or the like—is poured into the upper end of the mouth of the jar to rest on top of the retainer C, the sealing material extending into the mouth of the jar to a suitable depth—that is, nearly to the top of the edge 60 of the jar. Now it will be seen that the sealing material in connection with the retainer C forms a perfect hermetic sealing for the mouth of the jar, so as to exclude air, moisture, or other external influences from the 65 contents of the jar, thereby preventing deterioration of the goods. The cap B is screwed on in the usual manner to close the jar.

By the use of the retainer C the contents of the jar are held against movement therein 70 when the jar is handled, and in case the jar is filled with fruits contained in a preserving liquid the retainer C presses the uppermost layer of the fruit below the level of the preserving liquid, so that all the fruit is sub- 75 merged in the liquid.

When it is desired to remove the contents of the jar, then the cap B is first unscrewed, after which the sealing material D is removed, and then the retainer is unscrewed to gain 80 access to the contents of the jar, which can now be removed from the mouth of the jar in the usual manner.

Having thus described my invention, I claim as new and desire to secure by Letters 85 Patent—

1. A jar having an external and an internal screw-thread at its mouth, a cap screwing on the external screw-thread, and a retainer screwing on the internal screw-thread, 90 as set forth.

2. A jar having a retainer screwing into the mouth of the jar, and a sealing material in the space between the retainer and the upper edge of the mouth of the jar, as set forth. 95

3. A jar having a retainer screwing in the mouth of the jar, and provided with a packing forming a screw-thread engaging a thread on the inside of the mouth of the jar, and a sealing material in the upper end of the 100 mouth of the jar, resting on the said retainer, as set forth.

4. A jar having a retainer screwing into the mouth of the jar, consisting of a disk,

and a peripheral packing forming a screw-thread for engaging a thread on the inside of the mouth of the jar, as set forth.

5. A jar having an internal screw-thread at its mouth, and a retainer screwing on the said internal screw-thread, as set forth.

In testimony whereof I have signed my

name to this specification in the presence of two subscribing witnesses.

JAMES ALBERT MAXSON.
